TESTING DEVICE

Edward G. Thomas, Toledo, Ohio, assignor to
 Toledo Scale Manufacturing Company, Toledo,
 Ohio, a corporation of New Jersey

Application February 17, 1930, Serial No. 428,932,
 and in Canada March 20, 1930

14 Claims. (Cl. 265—44)

This invention relates to testing devices and in particular to devices adapted to test sand or the like to determine the amount of moisture present. It is very important in concrete work that the cement, coarse aggregate, sand and water in the concrete mixture do not vary an appreciable amount from a standard which has been established by experiments, for example, text books on concrete practice list nearly a dozen faults which 5 arise through an excess of water. The most serious of these are probably that the strength of concrete is reduced; that the excess water occupies space in the concrete and later causes voids after drying out and also that the risk in freezing 10 in cold weather is greatly increased.

Sand and concrete aggregates under ordinary conditions always contain some moisture. It will be readily seen that sand which has been stored in a builder's supply yard shortly after a rain 20 will contain a far greater amount of moisture than after having been lying in a dry atmosphere for some time and the actual amount of sand in a weighed quantity is less than the weight indicated by the scales as the moisture present is responsible for part of the weight. The weight of 25 water present in sand must be deducted to establish the actual weight of the sand. The amount of the water present in the sand should also be deducted from the quantity which is later added 30 when the concrete is mixed.

My invention, therefore, has for its principal object means for determining the amount of moisture in sands or similar material so that the actual amount of such material may be determined.

Another important object is the provision of means wherewith an unknown sample may be compared to a standard.

A still further object is the provision of means 40 wherewith the amount of standard sample can be definitely and accurately determined.

A still further object is the provision of means for indicating the percentage of moisture present in the sample.

These and other objects and advantages will be apparent from the following description wherein reference is had to the accompanying drawings and wherein similar reference numerals designate similar parts throughout the several views.

50 In the drawings:—

Figure I is a front elevational view, a portion being broken away, of the device embodying my invention.

Figure II is a plan view thereof, a part being 55 broken away.

Figure III is an end elevational view.

Figure IV is a fragmentary section substantially along the line IV—IV of Figure I.

Figure V is an enlarged section along the line 5 V—V of Figure I showing the bearing loop 60 bracket.

Figure VI is a fragmentary side elevational view taken substantially along the line VI—VI of Figure I.

Figure VII is a fragmentary view of the position adjusting means. 65

Referring to the drawings in detail, the scale to which I have shown my invention attached is the well known Toledo fan scale and I will describe it only in so far as is necessary to adequately describe my invention. Mounted upon one end of the base 1 is a base horn 2. This base horn is provided with suitable bearings in which the fulcrum pivots 3 and 4 of a load supporting lever 5 are mounted. Pivots 6 and 7 which also 70 are secured to the lever 5 and extend laterally therefrom, support a load supporting spider 8 upon which the load receiver or load scoop 9 is mounted. The opposite end of the lever extends into a housing 10 and is connected by 75 means of a link 11 to a load counterbalancing pendulum 12 which is pivotally supported within the said housing. A hand 13, secured to the pendulum 12, co-operates with a chart 14 fixed in the upper portion of the housing 10 to indicate, 80 at different times, the amount of the sample and the amount of moisture in the sand.

The lever 5 has laterally extending arms 15 and 16 to which a horizontally positioned frame 17 is fastened. This frame 17 is provided with 85 two upwardly extending portions 18 and 19 which are provided with apertures in which a threaded shaft 20 is turnably positioned. One half of the threads on the shaft 20 are right-handed and the other half are left-handed. The 90 shaft 20 is threaded through apertures in slidably mounted brackets 23 and 24 so that when the shaft 20 is turned by the knurled knob 25, secured to a projecting end equal movements are imparted to the brackets 23 and 24 but in 95 opposite directions. Depending from pivots 21 and 22 in the brackets 23 and 24 are bearing loops 26 and 27 which support depending hooked members 28 and 29 from which the sample buckets 30 and 31 are suspended. These buckets 100 with their attached parts are identical both as to weight and material, so that when similarly immersed, their loss of weight will be exactly the same. For a reason which will be explained later, it is necessary that the threaded shaft 20 105

be accurately located. An adjustment has therefore been provided of which an enlarged fragmentary view is shown in Figure VII. The end of the shaft 20 is turned down to a slightly smaller diameter to provide a shoulder. A washer 33 is secured in position against the shoulder by the pin 34. The projection 18 is provided with a threaded aperture in which a threaded bushing 35 is located. The turned down portion 10 of the shaft 20 extends through this threaded bushing and is prevented from displacement by another washer 36 which is secured to it by a pin 37. It will now be seen that the shaft 20 depends on this construction for its position. When 15 the threaded bushing 35 is turned by introducing a pin or a nail or a similar object in the holes 38, the position of this bushing will be changed laterally. The shaft 20 being free to turn, but prevented from lateral movement in 20 relation to the bushing 35 by the washers 33 and 36, will correspondingly change its position in relation to the lever and may thus be accurately positioned. The projection 18 is split so 25 that a screw 39 serves to clamp the bushing 35 in its position.

The principle on which this scale works is that of comparing a known weight of dry sand under water with an unknown quantity of sand containing moisture which is also submerged. It is obvious that the moist sample of sand weighing 2 30 pounds gross will have less than 2 lbs. net of sand in it and this amount of sand will weigh less than will an actual 2 lb. sample of dry sand. The downward pull of the samples when suspended from the pivots 21 and 22 will therefore be unequal 35 and a movement of the scale sufficient to counterbalance the counterbalanced force by an increase in the pendulum resistance will occur. Assuming an extreme case in which the sample 40 has as much water as sand, in other words, in the sample, there will be 1 pound of sand and 1 pound of water. When this sample is immersed and compared to the standard sample of dry sand, its pull will only be one half that of the dry sand sample. The pivots are so positioned 45 that the dry sand alone immersed in water will pull the indicator to the full capacity character on the chart. Therefore, if one half the pull of the dry sand sample is offset by the sample of sand under test, it will pull the indicator to one 50 half the capacity on the chart and at this point 100% is marked thereon. It will be seen that the sample buckets 30 and 31 must always be stationed an equal distance on either side of the 55 fulcrum pivots 3 and 4 in the main lever 5. To accomplish this, the hereinbefore described adjustment of the threaded shaft 20 has been provided, since the moisture in the sample in our supposed case is equal to 100% of sand in the 60 sample. If there are 80 parts of sand and 20 parts of water in the sample when this is immersed, its pull will be equal to $\frac{1}{3}$ that of a dry sample. The pendulum resistance therefore to supply the remaining force for counterbalancing the load will be $\frac{1}{3}$ the capacity of the scale and at this point a character denoting 25% is placed on the chart 14, since the weight of 20 parts of water is 25% of the weight of 80 parts of sand.

70 When it is desired to establish the moisture content in a sample of sand, the first operation consists in removing the sample buckets which are suspended from the movable pivots 21 and 22 which are stationed in the frame 17 which is a 75 part of the weighing lever. This is done only for

convenience since the scale is perfectly balanced for weighing when the pans are empty since the pans and attached parts are equal in weight. By removing them from the pivots, a standard sample, adapted for several tests, may remain undisturbed. A bracket 40 is fastened to the end of the base 1. This bracket has a bifurcated end in which a plunger 41 is mounted for vertical movement. Fastened to this plunger is a yoke 42. The ends 43 and 44 of the yoke 42 are shaped substantially like a trough having straight sides and a slotted opening in the bottom. The straight sides of the ends 43 and 44 are adapted to prevent the bearing members 26 and 27 from twisting when lifted from the pivots 21 and 22. The hook like members 28 and 29 extend through the slot in the bottom. This slot is of sufficient width so that the sides will not interfere with the hook-like members 28 and 29 when the bearings are on the pivots and the device is in use. The plunger 41, when pushed upwardly, carries the yoke 42 with it. The trough-like ends of the yoke 43 and 44 contact the bottom of the bearing loops 26 and 27 and continued movement of the plunger will lift them from the pivots 21 and 22. At 100 this point, a spring catch 45 will slip beneath the yoke 42 and hold it in that position. When this has happened, the scale per se is in a condition to weigh commodities which are placed in the commodity receiver 9 and indicate their weight on the chart 14 with the hand 13. In this scale only one weight character 14¹ has been placed thereon, namely the character representing the weight of a sample; in this case, 2 lbs., as in the operation, the determination of moisture 110 in sand is to be performed with 2 lb. samples. The indicia 14² designate the percentage of moisture in the sand. After the bearing loops have been raised from their pivots by means of the lifting arrangement, 2 lbs. of dry sand are carefully 115 weighed out. This 2 lb. sample is now placed in the sample bucket 31 and lowered by means of the lifting yoke 42 and plunger 41 into a tank 46. This tank is filled with water to a height so that when the sample buckets 30 and 31 are lowered, they are completely submerged. If the scale is adjusted correctly for sand of the particular 120 specific gravity being handled, the scale indicator should come to the full capacity mark. If it does not, the threaded shaft 20 provided with 125 the right and left handed threads which pass through the slidably mounted brackets 23 and 24, is turned until the position of the pivots 21 and 22 is so corrected that the indicator does register with the full capacity mark on the chart. The 130 provision to vary the lever arms of the brackets 23 and 24 by means of the right and left threads on the shaft 20, permits the adjustment of the scale to correspond to the actual specific gravity of various sand samples very readily and of quite 135 a wide range. The sample buckets 30 and 31 are then again removed from the pivots 21 and 22 and a 2 lb. sample of the moist sand is weighed out and placed in the bucket 30 leaving the dry sand sample undisturbed in the bucket 31. The containers are then again lowered so that the bearing loops 26 and 27 are suspended from the pivots 21 and 22 and the sample buckets are submerged. The scale will now indicate the percentage of 140 moisture in the moist sample referred to, the weight of the dry sand sample is the basis for this determination. It will be readily seen that when the dry sand sample in the bucket 31 is supported from the weighing lever 5 and the position of the supporting pivot adjusted so that the hand indi-

- cates its weight on the chart an equal weight of sand in the bucket 30 would offset the weight of the first mentioned sample and the scale would indicate zero. As long as the original dry sand 5 sample remains representative of the sand being used, it will not be necessary to weigh out a new dry sand sample, so that in further moist sand testing, it will only be necessary to weigh out the moist sample to be tested.
- 10 Having described my invention, I claim:
1. In a device of the class described, in combination, lever mechanism, counterbalancing and indicating means operatively connected to said lever mechanism, means for supporting upon said 15 lever mechanism a standard sample, means for supporting upon said lever mechanism a specimen to be tested, means for imparting buoyancy to said standard sample and to said specimen to be tested and means connected to said lever mechanism for indicating the ratio of deficiency in 20 weight of the sample to the actual weight of the standard sample.
  2. In a device of the class described, in combination, lever mechanism, means for supporting 25 two loads thereon, means connected to said lever mechanism to counterbalance the difference between said loads and means for varying the leverage of such loads relative to that of said counterbalancing means, said leverage varying 30 means operating to vary equally the leverage of each of said load supporting means.
  3. In a device of the class described, in combination, lever mechanism, means for supporting two loads thereon tending to counterbalance each 35 other, means connected to said lever mechanism to counterbalance the difference between such loads and means for varying the leverage of such loads relative to that of the counterbalancing means, said lever varying means operating to 40 vary equally the leverage of each of said load supporting means.
  4. In a device of the class described, in combination, lever mechanism, means connected thereto for counterbalancing and indicating the 45 weight of loads, load receivers connected to said lever mechanism to receive said loads and means for submerging said loads, said indicating means being adapted to indicate the differences of the submerged weights of said loads.
  5. In a device of the class described, in combination, lever mechanism, means connected thereto for counterbalancing and indicating the 50 weight of loads, and two load receivers mounted on said lever mechanism, said load receivers being 55 mounted for manipulative synchronous movement in opposite directions.
  6. In a device of the class described, in combination, lever mechanism, a shaft carried thereby, means connected thereto for counterbalancing 60 and indicating the weight of loads, and two load receivers mounted on said lever mechanism, said load receivers being mounted for manipulative synchronous movement in opposite directions on 65 said shaft, said shaft having means for longitudinal adjustment and locking means for said adjusting means.
  7. In a device of the class described, in combination, lever mechanism, means connected thereto for counterbalancing and indicating the 70 weight of loads, a main receiver supported on said lever mechanism, auxiliary load receivers pivotally mounted on said lever mechanism to receive said loads, and means for removing said auxiliary load receivers from their pivotal mounting on the lever mechanism.
  8. In a device of the class described, in combination, lever mechanism, means connected thereto for counterbalancing and indicating the weight of loads, a main load receiver supported on said lever mechanism auxiliary load receivers pivotally mounted on said lever mechanism to receive said loads, and means for simultaneously removing said auxiliary load receivers from their pivotal mounting on the lever mechanism. 80
  9. In a device of the class described, in combination, lever mechanism, means connected thereto for counterbalancing and indicating the weight of loads, a main load receiver supported on said lever mechanism auxiliary load receivers pivotally mounted on said lever mechanism to receive said loads, and means for simultaneously removing said auxiliary load receivers from their pivotal mounting on the lever mechanism and means for retaining said auxiliary load receivers in their removed position. 85
  10. In a device of the class described, in combination, means for simultaneously weighing against each other a sample of moist sand and a sample of surface dry sand and means for submerging said samples during such weighing operation, said weighing means including a lever and means for supporting said samples therefrom at equal distances from its fulcrum. 90
  11. In a device of the class described, in combination, means for simultaneously weighing against each other a sample of moist sand and a sample of surface dry sand and means for submerging said samples during such weighing operation, said weighing means including a lever, means for supporting said samples therefrom at equal distances from its fulcrum and means connected to said lever for automatically counterbalancing the excess of weight in water of the sample of surface dry sand over the weight in water of the sample of moist sand. 100
  12. In a device of the class described, in combination, means for simultaneously weighing against each other a sample of moist sand and a sample of surface dry sand and means for submerging said samples during such weighing operation, said weighing means including a lever, means for supporting said samples therefrom at equal distances from its fulcrum, means connected to said lever for automatically counterbalancing the excess of weight in water of the sample 110 of surface dry sand over the weight in water of the sample of moist sand and means connected to said automatic counterbalancing means for indicating the difference in weights in terms of percentage of moisture. 115
  13. In a device of the class described, in combination, means for simultaneously weighing against each other a sample of moist sand and a sample of surface dry sand and means for submerging said samples during such weighing operation, said weighing means including a lever, means for supporting said samples therefrom at equal distances from its fulcrum, means connected to said lever for automatically counterbalancing the excess of weight in water of the sample of surface dry sand over the weight in water of the sample of moist sand and means connected to 120 said automatic counterbalancing means for indicating the difference in weights in terms of percentage of moisture, said means including a chart marked with characters indicating percentage of moisture to the sand contained in the moist sample and an index and means whereby said chart and index are moved relatively to each other by 125 130

movement of said load-counterbalancing mechanism.

14. In a device of the class described, in combination, means for simultaneously weighing 5 against each other a sample of moist sand and a sample of surface dry sand and means for submerging said samples during such weighing operation, said weighing means including a lever, means for supporting said samples therefrom at 10 equal distances from its fulcrum, means connected to said lever for automatically counterbalancing the excess of weight in water of the sample of surface dry sand over the weight in water of the

sample of moist sand and means connected to said automatic counterbalancing means for indicating the difference in weights in terms of percentage of moisture, said means including a chart marked with characters indicating percentage of moisture to the sand contained in the moist sample and an index, means whereby said chart and index are moved relatively to each other by movement of said load-counterbalancing mechanism and means for simultaneously proportionally varying the effective lengths of the arms of said lever. 80 85
